CLAIM

We claim the ornamental design for a charging connector, as shown and described.

DESCRIPTION

FIG. 1 is a front isometric view of a charging connector with a portion of a cable shown in dashed lines for environmental purposes.

FIG. 2 is a front elevation view thereof.

FIG. 3 is a rear elevation view thereof.

FIG. 4 is a right side elevation view thereof.

FIG. 5 is a left side elevation view thereof.

FIG. 6 is a top plan view thereof; and,

FIG. 7 is a bottom plan view thereof.

The broken lines in the drawings illustrate environmental features and portions of the charging connector that form no part of the claimed design.
